UNITED STATES PATENT OFFICE.

WILLIAM E. MOODY, OF COLUMBUS, OHIO, ASSIGNOR TO JAMES ELLWOOD JONES, OF SWITCHBACK, WEST VIRGINIA.

LOADING MACHINE.

1,420,207.

Specification of Letters Patent. Patented June 20, 1922.

Application filed February 19, 1919. Serial No. 277,969.

To all whom it may concern:

Be it known that WILLIAM E. MOODY, a citizen of the United States, residing at Columbus, in the county of Franklin and State 5 of Ohio, has invented certain new and useful Improvements in Loading Machines, of which the following is a specification.

This invention relates to loading machines designed for use particularly in mine work 10 for gathering and loading the broken down coal into suitable receptacles. The type of machine to which this present application particularly relates is shown and described in Patent No. 1,362,889, issued December 21, 15 1920, to N. A. Newdick. In this type of machine, there is provided a conveyor pan and an endless conveyor of the side arm type operating thereover, the conveyor pan being itself pivotally mounted adjacent its 20 rear so that its front end may be caused to sweep back and forth over the mine floor to gather the coal prior to conveying it rearwardly. In this type of operation, trouble has frequently been encountered by the 25 front or nose end of the machine climbing the coal pile instead of forcing its way underneath it and it is this evil effect that my present invention attempts primarily to overcome.

With this construction in mind, therefore, 30 my invention resides essentially in the combination with a conveyor pan having a depressed forward end or nose portion, which conveyor pan is pivotally mounted adjacent its 35 rear end upon a suitable support and whose weight is sustained by the depressed front portion by direct bearing upon the floor, of means located on the underneath side of the nose portion and covering a comparatively small area thereof so that the 40 weight of the forward portion of the conveyor pan is correspondingly concentrated upon a small area. In this manner, any loose particles lying upon the floor of the 45 mine will be crushed because of the concentration of weight or if these particles should take the form of inequalities in the floor level such as small pieces of coal or slate which had not been completely loosened or separated from the floor proper, they are destroyed in some manner such as shearing be-

cause of the concentrated weight. One form in which my invention may be practiced is that of a peripheral band of comparatively small area located adjacent the edge of the 55 depressed portion whereby small particles may be brushed or sheared from their anchorage on the mine floor during the sweeping movement of the forward portion of the conveyor.

The preferred embodiment of my invention is shown in the accompanying sheet of drawings wherein similar characters of reference designate corresponding parts and 60 wherein.

Figure 1 is a small diagrammatical view illustrating the type of machine in connection with which my invention is employed.

Figure 2 is an enlarged plan view of the 65 forward depressed end or nose portion of 70 the conveyor pan shown in Figure 1, and

Figure 3 is a cross section taken on line 3—3 of Figure 2.

The unit shown in Figure 1 is similar in 75 fundamental respects to that described in the application above referred to and constitutes a supporting truck or base unit 1 having wheels 2 and 3 mounted in connection therewith. A conveyor pan 4 is provided and is pivotally mounted adjacent its 80 rear end about a vertical pivot 5 and is also so constructed so that it may swing about a horizontal pivot such as the rear axle 6. The extreme forward portion of the conveyor pan is provided with a depressed 85 end or nose portion 7 which nose portion is arranged and designed to slide over the mine floor. This nose portion also carries a sprocket wheel 8 over which the conveyor chain 9 passes, the latter being provided 90 with flights 10 for attacking the coal to gather it and convey it rearwardly to any desired receptacle.

The depressed end of the conveyor pan 95 usually takes the form of a flat sheet of material 11 and as the inclined portion 12 is reached, sides 13 flare upwardly to form a chute proper. The flight arms 10 are preferably bent at their forward ends as shown at 14 and carry cutters of any suitable form 100 such as shown at 15 at their extreme ends so as to scrape the mine floor and loosen

as much material as may remain thereon as possible. These flights and chains operate over the conveyor pan in any suitable manner, it not having been deemed necessary in 5 this case to describe the source of motive power or the manner in which it is applied.

It will be noted that the weight of the conveyor pan and the contents being conveyed is sustained at two points, namely 10 about the rear vertical pivot mounting and the depressed forward end which is arranged to rest directly upon the floor. In order to concentrate this weight upon a comparatively small area to thereby produce 15 a brushing effect upon any material over which the pan may pass which is susceptible of being crushed, I have provided the peripheral portion of this depressed end with a comparatively narrow band 16 whose 20 outer edge is chamfered to knife form as shown at 17. By this arrangement the only frictional contact of the forward end of the mine floor is along the bottom of the band 16 and consequently the hollowed portion 25 18 between the sides of the depressed end permit the machine to operate over various inequalities in the mine floor without lifting the edge portion 16 off the floor. Likewise, any tendency to riding or cramming 30 up the coal pile is eliminated because the entire weight is concentrated upon a comparatively small area which will either crush or shear the loose material upon the floor as it sweeps back and forth.

35 From the foregoing description taken in connection with the accompanying sheet of drawings, it will therefore be apparent that I have provided a type of machine embodying a highly utilitarian structure. 40 This structure is such that any tendency of the forward or nose portion of the machine to leave the floor is entirely eliminated.

What I claim is:

1. In a loading machine, a portable base 45 unit, a conveyor pan including a depressed forward end or nose portion arranged to operate in advance of said base unit, a pivotal connection between said pan and base unit, said connection serving to permit the 50 nose portion to sweep horizontally back and forth across the floor of a mine, and means located on said nose portion and projecting below the under side thereof and serving to permit of the concentration of the weight 55 imposed upon the forward end of the pan thereon.

2. In a loading machine, a portable base 60 unit, a conveyor pan including a depressed forward end or nose portion, a pivotal connection between said base unit and pan and serving to permit of back and forth swinging movement of said nose portion across the floor of a mine and at positions in advance of said base unit, and means located 65 on the periphery of said nose portion and

projecting below the under side thereof and serving to concentrate the weight of the forward end of said pan thereon, said means being provided with a peripheral downwardly and outwardly inclined surface. 70

3. In a loading machine, a conveyor pan including a depressed forward end or nose portion, a supporting truck for the rear portion of said pan and upon which the pan is mounted for pivotal movement about a 75 vertical axis, said nose portion being arranged to operate in advance of said truck and directly over a mine floor, and means located on the under side of said nose portion and covering a comparatively small area 80 thereof, said means serving to permit of the concentration of the weight of and on the forward portion of the pan upon the reduced bearing surfaces provided by said means. 85

4. In a loading machine, a conveyor pan including a depressed substantially flat forward end or nose portion, a supporting truck for the rear portion of said pan and to which the latter is pivoted, the said nose portion 90 of the pan being arranged to operate directly over a mine floor and to receive the weight of the material to be loaded thereon, a relatively narrow peripheral strip secured to the under edge of said nose portion, said strip projecting below said nose portion to confine the weight of and on that portion of the machine upon the reduced bearing surfaces provided by said strip. 95

5. In a loading machine, a conveyor pan 100 including a depressed forward end or nose portion, a supporting truck for the rear portion of said pan and to which the latter is pivotally connected, whereby said nose portion will be permitted to oscillate over a mine 105 floor at positions in advance of said truck, a relatively narrow peripheral strip located along the under marginal edges of said nose portion, said strip serving to permit of the concentration of the weight of and on the 110 forward portion of the machine upon the comparatively small bearing surfaces provided by said strip, and an outwardly and downwardly inclined peripheral surface formed upon said strip. 115

6. In a loading machine, a portable base unit, a conveyor pan including a depressed forward end or nose portion mounted upon said base unit in such manner as to permit the nose portion to have a back and forth 120 sweep movement across the floor of a mine, conveying mechanism carried by said pan, and downwardly and outwardly inclined surfaces provided upon the marginal edge of said nose portion and serving upon sweep 125 movement of said pan to maintain the nose portion thereof beneath the material to be loaded and in engagement with the mine floor.

7. In a loading machine, a portable base 130

unit, a conveyor pan including a depressed forward end or nose portion, the latter being capable of swinging back and forth across the floor of a mine and beneath the material to be loaded, and inclined surfaces provided upon said nose portion around the peripheral edges thereof, whereby upon

sweep movement of said nose portion the pressure exercised by said material upon the inclined surfaces will serve to maintain the nose portion beneath the material to be loaded.

In testimony whereof I affix my signature.
WILLIAM E. MOODY.
